(57) **CLAIM**

The ornamental design for a tire bead breaker, as shown and described.

DESCRIPTION

FIG. 1 is a perspective view of a tire bead breaker showing my new design;

FIG. 2 is a right side elevational view thereof; the left side elevational view being a mirror image of the right side;

FIG. 3 is a top plan view thereof;

FIG. 4 is a bottom plan view thereof;

FIG. 5 is a rear elevational view thereof; and,

FIG. 6 is a front elevational view thereof.

The broken line portions of the tire bead breaker are for illustrative purposes only and form no part of the claimed design.
